SIGNAL CONTROL MECHANISM

Manious Garl, deceased, late of Akron, Ohio, by
 Linnie Garl, executrix, Akron, Ohio, assignor
 to Linnie Garl

Original application March 26, 1931, Serial No.
 525,510, now Patent No. 1,921,615, dated August
 8, 1933. Divided and this application July 3,
 1933, Serial No. 678,972

9 Claims. (Cl. 177—378)

The present invention relates to signal control mechanism which is primarily adapted for use in combined police and fire alarm systems such as described in my copending application Serial 5 No. 525,510, filed March 26, 1931, Patent No. 1,921,615, dated August 8, 1933, of which this case is a division. For a more complete understanding of these systems, reference may be had to the parent case, although it is to be understood that 10 my signal control mechanism is not limited in its use with such combined systems, since its applicability to many types of alarm or signal systems is recognized by me and will be apparent to those skilled in the art.

15 For the purpose of illustrating and explaining the construction and functions of my signal control mechanism in its embodiment in a signal system, the general system of my copending case may be briefly described as an alarm system consisting of two or more central stations, or most generally these central stations will consist of a 20 single central station at the fire department headquarters and another central station at the police department headquarters. Each of these 25 central stations for the purpose of description may be said to maintain outlying stations in the field which may be widely separated and which may vary in number. These outlying stations consist of the conventional street alarm boxes 30 having housed therein alarm and telephonic instrumentalities adapted to function in separate energized circuits connecting each alarm box with the central stations respectively. Each 35 alarm box is of conventional design and is provided with the usual inner door on which the various instrumentalities, both signal and telephonic, are mounted. The outer door is provided with a shatterable glass seal adapted to be broken in the usual manner when a fire alarm is 40 to be sent into the fire department headquarters. Means is provided for the use of the alarm box as a field post signal and telephonic station to the police department central station or headquarters by simply opening the outer door, the 45 signal and telephonic instrumentalities being automatically introduced, upon opening of the outer door, into the police department circuit. Provision is made for temporarily shunting the 50 signal and telephonic instrumentalities out of the fire department circuit to permit the functioning of the fire circuit from other outlying stations to be maintained operable as usual and to prevent reception of the police signal at the fire department headquarters. Means is similarly provided for shunting the signal and tele-

phonic instrumentalities out of the police department circuit and introducing them into the fire department circuit when a fire alarm is sent into the fire department, such means being operable only when the outer door remains closed 5 or when the door operated instrumentalities are manually operated. In order that a general alarm may be sent in successively by the same police officer to both central stations, as for example when a fire is supposed to be of an incendiary origin, the switch mechanism operated by the outer door is manually controllable so that signal or telephonic communication may be first sent in to the police department and immediately thereafter to the fire department, or vice versa. 15

It is an object of the present invention to provide a suitable signal control mechanism, preferably of the rotary disc type, which automatically introduces the signal instrumentalities into the police or fire department circuit, as the case may 20 be, incident to the tripping of the signal mechanism. Provision is also made for automatically shunting out the signal instrumentalities upon completion of the transmission of the signals.

Another object of the invention is to provide a 25 shunt which is so positive in operation that poor or loose electrical contact is avoided, and when the shunt contact members are closed there is no likelihood of the same becoming opened by accident as by jarring the mechanism. 30

The invention has for a further object the utilization of a conventional driving and escape- 35 ment mechanism for the actuation of the signal instrumentalities, which mechanism is tripped for actuation and automatically stopped upon completion of the signals, in a novel and distinct manner, the novel construction and arrangement of the control mechanism contributing in a large measure to the efficiency and effectiveness of the 40 signal system as a whole.

Other and further objects and advantages of the invention will be hereinafter set forth and the novel features thereof defined by the appended claims. 45

In the drawings:—

Fig. 1 is a diagrammatic view of the electrical circuits and signal and telephonic instrumentalities of a complete police and fire alarm system, in which my signal control mechanism may be 50 embodied by way of example of one adaptation of the same.

Fig. 2 is a front elevation of the clockwork gear train mechanism with the inner door removed, showing the same in its normal position when 55

the outer door is shut and when the mechanism is ready to be tripped to send in a fire alarm.

Figure 3 is a fragmentary view, similar to Fig. 2, showing the clockwork gear train mechanism in the position occupied when the police alarm lever has been tripped and when the outer door is open to shunt the signal and telephonic instrumentalities out of the fire department circuit and install the same into the police department circuit.

Figure 4 is a fragmentary view similar to Figures 2 and 3, showing the clockwork gear mechanism occupying the proper position after a fire alarm has been sent in to the fire department headquarters, with the outer door shut and before the clockwork mechanism has been reset by the chief officer of the fire patrol.

Figure 5 is a fragmentary side elevation of the arrangement of parts shown in Figure 4.

Figure 6 is a front elevation of the detached inner door panel showing the signal and telephonic instrumentalities mounted thereon.

Figure 7 is a bottom view of the showing in Figure 6.

Figure 8 is a fragmentary front elevation of an alarm box having hinged inner and outer door panels with associated signal and telephonic instrumentalities mounted thereon in operative relation.

In all of the above described views, like characters of reference are employed to designate like parts throughout.

Referring now to Figure 1, unit 4 designates diagrammatically the police department headquarters central station including a police alarm relay 10, a telephone unit 11 in multiple therewith, and an energizing battery 12, all operatively connected in a three wire circuit 13 connected with various outlying stations or field posts.

Unit 2 represents diagrammatically a similar central station for the fire department, including a fire alarm relay 14, telephone instrumentalities 15 in multiple therewith and an energizing battery 16, all operatively associated in the circuit 17. One of the wires 103 of the three-wire circuits 13 and 17, may be termed the fire department line or circuit, this being the upper wire of the three shown in the upper extremity of the wiring diagram of Fig. 1. As shown, the lower wire 100 of the three-wire group is the police department line, and the center wire 104 is the common or ground wire. It is understood that the relative positions of these wires is immaterial.

Unit 3 represents diagrammatically the signal and telephonic instrumentalities operatively mounted within one of the outlying street alarm boxes as connected in the police department circuit and including clockwork controlled signal instrumentalities 18, telephonic instrumentalities 19, a shunt mechanism 20, and a transfer switch 21 for shunting the signal and telephonic instrumentalities out of the police or fire department circuits according to whether the outer door for the box is respectively closed or open.

Unit 4 represents diagrammatically the same or another outlying station represented by unit 3, with the signal and telephonic instrumentalities connected in the fire department circuit 17, and showing a telephone signal switch 22 adapted for use in attracting the attention of the central station operator preliminarily to establishing telephonic communication with the central station of the fire department.

Referring now to Figs. 6, 7 and 8, the alarm

box is shown at 23. This box is of the conventional type and has hinged thereto as at 24 an inner door panel 25 on which are mounted the signal and telephonic instrumentalities. Hinged to the alarm box 23, as at 26, is an outer door panel 27 having a shatterable window 21, the door being shown in its open position in Fig. 8.

The signal instrumentalities shown at 18 in units 3 and 4 of Fig. 1 and in Fig. 7 are comprised of a clockwork unit 28 secured by means of bolts 29 (see Fig. 8) to the rear of the panel 25. This clockwork unit comprises an alarm wind and trip lever 30 positioned on the front of the panel 25, and a fire alarm trip lever 31 operable by means of a handle 31' and extending forwardly of the panel 25.

The telephonic instrumentalities 19 are comprised of the usual receiver hook 32, a receiver 33 mounted within a pocket 34 in the front of the panel 25, and a transmitter 36 secured to the rear of the panel 25 and having a mouthpiece 36' on the front side of the panel, together with the usual telephone switch assembly 37 selectively connected in multiple with the police and fire alarm relays 10 and 14, as clearly shown in unit 1 of Fig. 1.

Operatively associated with the inner door panel 25 is a transfer switch 21 as disclosed in my Patent No. 1,921,615 of which this case is a division for selectively rendering the signal and telephonic instrumentalities 18 and 19 operable in the fire department or police department circuits 13 or 17. This switch is operable by a plunger 38 extending outwardly of the front wall 35 of the panel 25 for such selective control. The switch in its normal position with the outer door panel 27 closed serves to maintain the signal and telephonic instrumentalities in the fire department circuits, but upon opening of the outer door panel this switch is automatically operable, by an arrangement of parts more fully to be described hereinafter, to exclude these instrumentalities from the fire department circuit and install the same in the police department circuit.

The telephone signal switch 22 is operable by a push pull plunger 39 extending forwardly of the panel 25 to cause a signal apparatus (not shown) at the fire department headquarters to notify the desk attendant that the telephone is 50 to be used.

Referring now to Figs. 2, 3, 4 and 5, the clock work operated signal unit 28 is shown in a number of operative positions. The specific spring actuated gear train which causes movement of 55 the novel signal control is of conventional design and may be similar to that shown in the patent granted to J. and W. H. Sidall, No. 1,203,420, dated October 31, 1916. No claim is made to the novelty of this driving mechanism, the novelty of 60 the clock work unit residing rather in the signal control itself. The clock work unit is shown as comprising the usual frame 40 including a plate 41. Journalled in this plate 41 is a shaft 42, corresponding to shaft 23 of Sidall, upon which the 65 wind lever 30 is mounted and secured. This shaft 42 has applied thereto by the spring of the clock work unit a torque normally urging the same in a counterclockwise direction. The shaft 42 has keyed thereto a swing arm 43 having oppositely 70 extending radial portions 44 and 45, the arm 44 being slightly longer than the arm 45. The arm 45 is provided with an abutment surface 46 adapted to engage the pin 47 on a sliding plate 48. The plate 48 is provided with a slot 49 through 75

which there extends a screw 50 which is threadedly receivable in the plate 41. The plate 48 is of elongated shape and one end thereof has a roller 51 mounted thereon, which roller is formed of insulating material. Secured to a post 52 and electrically connected thereto, is a conducting leaf spring 53 having one end thereof bearing against the roller 51 as at 54 and normally urging the roller and the elongated plate 48, to which it is attached, downwardly in a direction opposed to the direction of movement of the plate as urged by the engagement surface 46 bearing against the pin 47. In the normal position of the arm 43 the abutment surface 46 bears against the pin 47 and holds the plate 48 in the position shown in Figure 2 with the leaf spring 53 under tension. A bar 54' formed of suitable insulating material is secured by insulated bolts 55 to the plate 41. This bar 54' has a contact plate 56 secured thereto, which plate is connected through an electrical connection in the form of a copper strip 57 to a contact post 58, (Fig. 2 and units 3 and 4 of Fig. 1), electrically connected to one contact 59 of the circuit breaker mechanism 60. The contact post 58 is also electrically connected to the transfer switch 21 in a manner more fully described in my aforementioned patent. The post 52 which has the leaf spring 53 secured thereto is electrically connected to the movable arm 61 of the telephone receiver hook 32. This post 52 is also electrically connected to the other contact 62 of the circuit breaker mechanism 60. (See unit 3, Fig. 1.) In the normal position of the mechanism the roller 51 maintains the shunt, comprising of the contact plate 56 and the leaf spring 53, closed in order to shunt the signal mechanism out of the circuit. Upon tripping of the circuit breaker mechanism in a manner to be more fully described, the shunt is opened to enter the signal mechanism into the circuit for operative use while the code signal is being given in a conventional manner. The shunt is operable in this manner to exclude or include the signal mechanism in this circuit regardless of whether the signal mechanism is tripped for signalling in either the police department or the fire department circuit.

Referring again to Figure 2, wherein the normal position of the mechanism is shown with the outer door 27 closed and with the trip or swing arm 43 bearing against the pin 47, and with the shunt closed to exclude the signal mechanism from the alarm circuit, opening of the door 27 will cause the transfer switch 21 to shunt the fire department circuit completely out of the box and introduce the police department circuit to the various signal and telephonic devices thus far described within the box. By turning the wind lever 39 in a clockwise direction, as shown in Figure 8, the shaft 42 will be turned against the torque applied to it by the clock work spring mechanism and further wind the spring. This will cause the swing arm 43 to be turned in the direction of the arrow shown in Fig. 2, the limit of this turning movement being shown in Fig. 3 with the swing arm 43 bearing against the stop pin 63. Upon releasing of the wind lever 39 the escapement mechanism 64 will be set into action through the usual ratchet arrangement and the swing arm 43 will be rotated in a counter-clockwise direction. The turning of the swing arm 43 in a clockwise direction will cause the sliding plate 48 to be moved downwardly by the action of the contact spring 53 to open the shunt 20 and introduce the signal mechanism into the police department circuit main-

tained within the box by virtue of the outer door 27 being opened. Due to the turning of the swing arm 43 under the action of the clock work spring working on the shaft 42, and due to the operation of the escapement mechanism, the signal mechanism 60 (shown in Fig. 6) will be set into motion, effecting transmission of a suitable code signal, as for example, the box number, to the police department. By suitable prearrangement, this signal may indicate to the central station operator that the telephone should be answered.

It is understood that during this operation the outer door of the field box is open, and accordingly, the telephone instrumentalities have been introduced into the police circuit by the opening of the door operated shunt 90, 91, 92, incident to opening the outer door. Therefore, upon completion of the code signal and the automatic shunting out of the signal instrumentalities by the clockwork operated shunt 20 incident to such completion, the telephone instrumentalities are ready for use by lifting the receiver off the hook.

The signal mechanism comprises a rotatable disc 67 having a number of spaced radial projections 65 thereon adapted to successively engage a code lever 66 (see Fig. 6 and unit 3 of Fig. 1). Engagement of the projections 65 with this code lever 66 will cause opening and closing of the contact members 59 and 62 (see unit 3, Fig. 1) to carry the signal through the police department circuit 13 to the police department headquarters.

It will be seen, therefore, that when the outer door is open and when the wind lever 39 is rotated until the swing arm 43 engages the stop 63 and is then released the signal mechanism is operated in the police department circuit. The gearing of the disc 67 in the train of gears comprising the clock work mechanism is such that substantially one revolution of the disc will take place while the shaft 42 rotates throughout an arc sufficient to carry it from the position shown in Fig. 3 to the position shown in Fig. 2. When the shaft has completed this rotation throughout the arc just specified, the radial arm 45 engages the pin 47, thereby closing the shunt 20 and throwing the signal mechanism out of the police circuit, into which it was previously introduced when tripped and during functioning of the signal apparatus in the police circuit.

It has been seen how the signalling mechanism 18 functions to cause a signal to be sent into police headquarters when the outer door is opened and when the wind arm 39 is operated. It has also been seen how the shunt 20 operates to permit this signal mechanism to function for signal purposes and later to exclude the signal mechanism after the signalling has ceased, and it will now be described how the trip handle 31' may be employed to send a signal caused by the signal mechanism 18 through the fire department circuit to the fire department headquarters. With the transfer switch 21 so positioned that the fire department circuit is introduced into the box and the various signal and telephonic instrumentalities adapted for use in the fire department circuit, means is provided whereby movement of the trip arm handle 31' in an arcuate slot 68 formed in the inner door 25 will release the swing arm 43 for further rotational movement throughout a wider arc than is permitted when the trip arm 30 is thrown. Thus the escapement mechanism 64, released upon

movement of the swing arm 43, will permit the circuit breaker disc 67 to make several revolutions to send in several series of signals to the fire department headquarters. To accomplish this the trip lever 31 is provided with a bifurcated end 69 and is pivoted at 70 to the inside of the inner door panel 25. The bifurcations of the end 69 straddle the pin 47 and movement of the lever 31 on its pivotal axis and through a small angle commensurate with movement of the trip handle 31' in the slot 68 will shift the pin 47 (see Fig. 2) from the short arm 45 of the swing arm 43, thereby leaving the swing arm free to rotate under the action of the coil spring 15 of the clock work mechanism as governed by the escapement mechanism 64. The long arm 43 may then swing in a counter-clockwise direction from the position shown in Fig. 2 to the position shown in Fig. 4. During the movement of the swing arm 43 the escapement mechanism 64 is in operation. A locking means is provided for the escapement mechanism in the form of a pivoted latch member 73, (see Figs. 2, 3, 4, and 5). This latch member is substantially triangular in shape and is provided with an offset flange 74. A pin 75 extends completely through the latch member adjacent one corner and a leaf spring 76 secured to a post 77 has a bearing surface 78 thereon normally resting on the pin 75 in the position shown in Fig. 3. The long end 44 of the swing arm 43 is provided with a projection 79 (see Fig. 4) which engages the offset portion 74 of the latch member 73 upon completion of the stroke of the swing arm when tripped by the trip lever handle 31'. The play afforded by the slot 49 in the sliding plate 48 permits the projection 79 to engage the offset portion 74 and by a bell crank lever action throw the pin 75 in the latch member 73 toward the escapement mechanism 64, (see Fig. 5), to stop the escapement of the clock work mechanism and to stop movement of the breaker disc thereby shutting off the signal. As the long end 44 of the swing arm 43 engages the pin 47 at the end of its stroke, the sliding plate 48 is carried upwardly, together with the roller 51 thereon, and the shunt 20 is closed to shunt the signal mechanism, which has completed its function, from the circuit. In unit 4 of Fig. 1 the signal switch 80 is shown as being in series in the fire department circuit. This switch is of the push pull type and upon outward pulling of the plunger 39 the circuit is broken and a signal device at the fire department headquarters is operated. This signal device may be of any suitable type, as a bell, light, or the like, and upon functioning of the same the operator at the fire department headquarters is notified that he is to pick up the telephone for communication.

Now, let it be assumed that the combined system herein described is to be used for transmitting an alarm to the fire department, a fire in an outlying district having been discovered. A civilian or some person runs to the nearest field box and breaks window 27', exposing trip lever handle 31'. Thereupon, the handle 31' is shifted in the slot 68, thereby releasing arm 45 of the signal control mechanism from abutment with pin 47, so that the clockwork operated shunt 20 automatically opens, introducing the signal instrumentalities into the fire department circuit, the code signal being automatically given in a conventional manner incident to the release of arm 45 from engagement with abutment pin 47. It is understood that the transfer switch

21 establishes the proper circuit, which in this case is the fire department circuit, due to the fact that the outer door of the field box is closed, and the transfer switch is thereby held by the door to establish this circuit, as diagrammatically shown in unit 4 of Fig. 1. Tracing the circuit over which the signal impulses flow from the code breaker contacts 59, 62, and starting from post 58 of unit 4, the circuit is as follows: post 58, wire 100, lefthand contact finger 84 of 10 transfer switch 21 of unit 4, left hand contact bar 83, lefthand contact finger 81, wire 101, thru telephone call switch 22, wire 102, over fire department line 103 to righthand contact finger 81 of transfer switch 21 of unit 3, contact bar 15 82 of unit 3, lefthand contact finger 81 of unit 3, back to line 103 and on to fire department relay 14, thru relay 14 to battery 16, and from battery 16 back over the ground or common wire 104 to wire 105 connected thereto at the extreme 20 right end of the figure, righthand contact finger 81 of transfer switch 21 of unit 4, righthand contact bar 83, righthand contact finger 84, wire 106, thru door shunt 90, 91, 92 (the door, and consequently the shunt, being closed) to contact 62, interrupter contact 59, back to post 58 from which the tracing started. In tracing this circuit from unit 4, and assuming unit 3 is another box some distance away, transfer switch 21 of unit 3 and door operated shunt 90, 91, 92 30 of this unit would normally be in the same position as in unit 4, instead of as shown in unit 3, if the outer door of unit 3 is closed, as it normally is. In that event, fire department line 103 can be traced thru from 102 of unit 4, thru 35 unit 3 to relay 14 in an obvious manner. As shown in unit 3, however, fingers 81 of transfer switch 21 of this unit are connected by bar 82, shortening the circuit somewhat, as in the case where transfer switch 21 of unit 3 happens to be in a 40 position for use of this box for communicating with the police department.

Having shown the circuit over which the code signals are transmitted to the fire department, and bearing in mind that the operation of the trip 45 handle 31' permits a series of complete signals to be sent, say, for example, several repetitions of the code number of the box, completion of the signals causes automatic locking of the drive mechanism for the signal mechanism and also 50 closing of shunt 20 (see Fig. 4), thereby excluding the signal instrumentalities from the circuit until the drive mechanism is rewound and tripped again. When the fire company arrives at the scene of the fire, a man may be detailed to re- 55 place the glass window 27' and rewind the drive mechanism, the latter being accomplished by opening the outer door of the field box to expose the winding arm 30 and rotating this arm 30 in a clockwise direction to the position shown in 60 Fig. 2, in which position the parts are conditioned for immediate or subsequent sending of alarms. If this man, or one of the fire company, wishes to communicate with the fire department, he may do so by opening the outer door of the 65 field box, if it is not already open, and manually holding the transfer switch 21 in the position it normally occupies when the door is closed, whereupon, pulling out telephone call switch button 22 momentarily will attract the attention of 70 the fire department central station operator. Then by lifting the receiver off the hook, he may talk with the operator. Under these conditions, it will be remembered that opening the outer door of the field box opens shunt 90, 91, 92; so that 75

the telephone instrumentalities are automatically introduced into the circuit, which is the same circuit as that described in detail for the transmission of the code signals. In other words, the telephone is substituted for the signal instrumentalities, the latter having been automatically shunted out upon completion of the code signals, and for this reason, the circuit will not be traced in detail again. It will be noted that the telephone instrumentalities of the fire department central station are connected in multiple with the relay 14, as shown in unit 2 of Fig. 1, so that in the case of telephone communication these instrumentalities function in place of relay 14, the operation of which was fully described in specifically describing the complete circuit.

Now let it be assumed that the system is normal and a police officer goes to one of the many boxes of the system for the purpose of communicating with police headquarters. To accomplish this, he opens the outer door of the field box, thereby causing the transfer switch 21 to automatically assume a position establishing the circuit to the police department central station, as shown in unit 3 of Fig. 1. Opening the door also automatically opens the shunt 90, 91, 92, so that the telephone instrumentalities are conditioned for use in this circuit. To get the attention of the police central station operator, the officer rotates arm 30 of the signal control mechanism from the position of Fig. 2 to the position of Fig. 3. This opens shunt 20 and introduces the signal instrumentalities in the circuit. When arm 30 is released after being moved to the position of Fig. 3, it returns to the position of Fig. 2, thereby transmitting a code signal to the police department central station, just as in the case of the fire code signal previously described, although in the present instance, the signal is not repeated as in the case where trip handle 31' is shifted for sending the signals to the fire department. In other words, a single set of signals is sent to the police department, preferably sufficient to merely identify the position from which the call is made, as by giving the box code number once, this signal serving to attract the attention of the police central station operator, and indicating that the operator should answer the telephone.

The circuit over which these signals are sent is as follows: Starting at post 58 of unit 3, the impulses pass over wire 100' to the lefthand contact finger 84 of transfer switch 21 of unit 3, lefthand contact bar 83, lefthand contact finger 35, wire 120, to police department line 110, police department relay 10, thru the relay to battery 12, from battery 12 to common or ground wire 104, over wire 104 to wire 121 connected thereto at the extreme right of the diagrammatic view, wire 121 to righthand contact finger 85 of transfer switch 21 of unit 4, contact bar 86 of unit 4, lefthand contact finger 85 of unit 4, wire 122, line 110, righthand contact 85 of transfer switch 21 of unit 3, righthand contact bar 83 of unit 3, righthand contact finger 84, wire 123, lower contact point associated with receiver hook 61 of unit 3, receiver hook, to contact 62 of the signal mechanism, interrupter contact 59, and back to post 58 from which the tracing was started. Upon completion of the code signal, shunt 20 of unit 3 automatically closes and the signal instrumentalities are shunted out of the circuit. The police officer at the box then lifts the receiver off of the hook and

verbal communication may be had with the central station operator.

If the police officer wishes to communicate with the fire department central station, he may do so by following the procedure previously described in conjunction with the fire department circuit; that is, by holding in the transfer switch 21 manually, momentarily pulling out the telephone call switch 22 to attract the attention of the fire department central station operator, and then lifting the receiver off of the hook. It is notable that in the case of the fire department signal, the signal instrumentalities are not used for attracting the operator's attention as in the case of the police department central station operator. This is because it is desirable to arrange the mechanism so that whenever a code signal is sent over the fire department circuit, it indicates a condition of emergency, additional signal apparatus being employed under control of the telephone call switch 22 for the purpose of indicating desire for telephone conversation over the fire department circuit. For the police department circuit, a suitable system of calls can be worked out to convey certain information to headquarters without using the telephone. For example, by operating lever 30 from the position of Fig. 2 to Fig. 3 position, twice in succession, the succession of code signals may indicate that the officer needs help and does not care to ask for it over the telephone for certain reasons. Operating the lever 30 three or four times in succession may denote a condition of extreme emergency, such as a riot, etc. Similarly, the fireman may communicate with the police department central station by following the procedure above described for the police department circuit.

Accordingly, it will be understood that the combined system is extremely flexible and affords protection far superior to that possible with systems heretofore known.

The operation of the control mechanism and associated system will be apparent from the foregoing description, inasmuch as the various elements, units and combinations of units have been described both as to their structure and as to their operation singly and in combination with each other where the occasion required.

The invention is not to be limited to the exact arrangement of parts shown in the accompanying drawings and described in the specification, as various changes in the detail of construction may be resorted to without departing from the spirit of the invention. Only insofar as the invention has been particularly pointed out in the accompanying claims is the same to be limited.

Having thus described this invention, what is claimed as new and desired to secure by Letters Patent in the United States, is—

1. In a clock work mechanism for circuit breakers of the rotatable disc type, a swing arm including a short radial portion and a long radial portion operatively geared to the rotatable disc, a movable limit stop normally in engagement with said short radial portion of the swing arm, a second limit stop normally out of engagement with said swing arm, means for manually rotating said swing arm and for winding the clock work mechanism to an extent limited by engagement of the swing arm with the second limit stop but adapted upon manual release thereof to permit the short radial portion of the swing arm to rotate into engagement with the movable limit stop, and manual means for tripping the movable limit stop out of engagement with the swing arm.

arm to permit added rotation of the swing arm, said movable limit stop after the action of said tripping means being adapted to be engaged by the long radial portion of the swing arm after a predetermined rotation of the latter.

2. In a clockwork mechanism for circuit breakers of the rotatable disc type, a swing arm including a short radial portion and a long radial portion operatively geared to the rotatable disc, a movable limit stop normally in engagement with said short radial portion of the swing arm, a second limit stop normally out of engagement with said swing arm, means for manually rotating said swing arm and for winding the clockwork mechanism to an extent limited by engagement of the swing arm with the second limit stop but adapted upon manual release thereof to permit the short radial portion of the swing arm to rotate into engagement with the movable limit stop, and manual means for tripping the movable limit stop out of engagement with the swing arm to permit added rotation of the swing arm, said movable limit stop after the action of said tripping means being adapted to be engaged by the long radial portion of the swing arm and moved therewith for a predetermined rotation of the latter, and an electrical shunt mechanism operably associated with said tripping means for shunting the circuit breaking mechanism out of the circuit incident to the last mentioned movement of the movable limit stop.

3. Signal control mechanism of the class described, comprising a clockwork mechanism, an arm mounted for rotation by said clockwork mechanism, a stationary shunt contact member, a movable shunt contact member including a resilient metallic strip fixed at one end with its free end engageable with but normally spaced from said stationary contact member, a slidable member mounted for sliding movements in opposite directions, an abutment carried by one end of said slidable member and cooperatively engaging the free end of said movable shunt contact member for moving said slidable contact member in one direction under the influence of the resiliency of the metallic strip, an abutment carried by the other end of said slidable member and engageable with said rotatable arm for movement of said slidable member in the opposite direction whereby to force said movable contact member into engagement with said stationary contact member.

4. Signal control mechanism of the class described, comprising a spring operated clockwork mechanism including a drive shaft normally urged for rotation in one direction by the spring, an arm fixed to said shaft for rotation therewith, a limit stop normally positioned in the path of rotation of said arm, said limit stop being movably mounted to afford a slight movement of the same incident to engagement of the said rotatable arm therewith, a pair of shunt contact members cooperating with said limit stop for closing said contact members incident to movement of said limit stop by the rotatable arm as aforesaid, and a wind lever fixed to the drive shaft of said clockwork mechanism and swingable in a direction opposite to the normal urging of the drive shaft and rotatable arm by the clockwork spring, the swinging of said wind lever as aforesaid withdrawing said rotatable arm from said limit stop to permit opening of said shunt contact members and setting said mechanism for operation to subsequently close said contact members incident to

engagement of said rotatable arm with said limit stop.

5. Signal control mechanism of the class described, comprising a spring operated clockwork mechanism, a drive shaft normally urged for rotation in one direction by the spring, a swing arm fixed to said shaft for rotation therewith and including relatively long and short radial arms, a limit stop normally positioned in the path of movement of one of said radial arms, said limit stop being movably mounted to afford a slight movement of the same incident to engagement of one of said radial arms therewith, a pair of shunt contact members cooperating with said limit stop for closing said contact members incident to movement of said limit stop by said radial arm as aforesaid, setting means for said limit stop affording a selective engagement with the long and short radial arms for selectively controlling the degree of rotation of said drive shaft, and a wind lever fixed to the drive shaft of said clockwork mechanism and swingable in a direction opposite to the normal urging of said drive shaft and radial arms by the spring, the swinging of said wind lever as aforesaid withdrawing the respective radial arm from said limit stop to permit opening of said shunt contact members and setting said mechanism for operation to subsequently close said contact members incident to engagement of one of said radial arms with said limit stop.

6. Signal control mechanism of the class described, comprising a spring operated clockwork mechanism, a drive shaft normally urged for rotation in one direction by the spring, a swing arm fixed to said shaft for rotation therewith and including relatively long and short radial arms, a limit stop normally positioned in the path of movement of one of said radial arms, said limit stop being movably mounted to afford a slight movement of the same incident to engagement of one of said radial arms therewith, a pair of shunt contact members cooperating with said limit stop for closing said contact members incident to movement of said limit stop by said radial arm as aforesaid, setting means for said limit stop affording a selective engagement with the long and short radial arms for selectively controlling the degree of rotation of the drive shaft, a wind lever fixed to the drive shaft of said clockwork mechanism and swingable in a direction opposite to the normal urging of said drive shaft and radial arms by the spring, the swinging of said wind lever as aforesaid withdrawing the respective radial arm from said limit stop to permit opening of said shunt contact members and setting said mechanism for operation to subsequently close said contact members incident to engagement of one of said radial arms with said limit stop, and locking means actuated by one of said radial arms for rendering said clockwork mechanism inoperative upon closing of said shunt contact members.

7. In a signal control mechanism of the class described, including separable signal contacts, a clockwork mechanism, circuit breaker mechanism including a code wheel operable by said clockwork mechanism and coacting with the signal contacts for making and breaking the signal contacts to transmit a signal, and trip means for normally preventing signal transmission operation of the aforementioned mechanisms, but adapted to be tripped to effect signal transmission, a shunt switch associated in multiple relation with said signal contacts, and comprising a stationary contact and a movable contact engageable with said stationary contact, said last-

mentioned contacts being self-opening, and means for forcibly closing said shunt switch contacts by the power of the clockwork mechanism, said last-mentioned means being effective to maintain said shunt switch contacts in closed engagement with each other whenever the signal contacts are inactive.

8. In a signal control mechanism of the class described, including separable signal contacts, a clockwork mechanism, circuit breaker mechanism including a code wheel operable by said clockwork mechanism and coacting with the signal contacts for making and breaking the signal contacts to transmit a signal, and trip means for normally preventing signal transmission operation of the aforementioned mechanisms, but adapted to be tripped to effect signal transmission, a shunt switch associated in multiple relation with said signal contacts, and comprising a stationary contact and a movable contact engageable with said stationary contacts, said last-mentioned contacts being self-opening, and means for forcibly closing said shunt switch contacts by the power of the clockwork mechanism, said last-mentioned means being effective to maintain said shunt switch contacts in closed engagement with each

other whenever the signal contacts are inactive, and said last-mentioned means being rendered ineffective, so as to permit the shunt contacts to open, incident to actuation of said trip means to effect signal transmission.

9. In a clockwork mechanism for circuit breakers of the rotatable disc type, a swing arm including a short radial portion and a long radial portion operatively geared to the rotatable disc, a movable limit stop normally in engagement with said short radial portion of the swing arm, means for manually rotating said swing arm and for winding the clockwork mechanism, and said means being adapted upon manual release thereof to permit the short radial portion of the swing arm to rotate into engagement with the movable limit stop, and manual means for tripping the movable limit stop out of engagement with the swing arm to permit added rotation of the swing arm, said movable limit stop, after the actuation of said trip means, being adapted to be engaged by the long radial portion of the swing arm after a predetermined rotation of the latter.

LINNIE GARN, 25

Executrix of Manious Garn, Deceased.
